UNITED STATES PATENT OFFICE.

WILLIAM H. ROSE, OF BALTIMORE, MARYLAND, ASSIGNOR TO AMERICAN OIL AND DISINFECTANT CO., OF NEW YORK, N. Y., A CORPORATION OF NEW YORK.

DISINFECTING APPARATUS.

No. 911,331.

Specification of Letters Patent.

Patented Feb. 2, 1909.

Application filed July 22, 1905. Serial No. 270,827.

To all whom it may concern:

Be it known that I, WILLIAM H. ROSE, a citizen of the United States, and resident of Baltimore, Maryland, have invented certain new and useful Improvements in Disinfecting Apparatus, of which the following is a specification.

Some forms of disinfecting fluids are non-volatile and do not serve for deodorizing purposes and it is advisable to use, in connection with such fluids, a deodorizing substance.

The object of the present invention is to produce a simple and compact combined apparatus for disinfecting and deodorizing.

According to the present invention I combine a disinfecting apparatus having means for producing a slight but constant flow of fluid with a deodorizing apparatus so arranged and combined that the two form practically one device, neither interfering with the operation or capacity of the other.

The invention will be described in connection with the accompanying drawing, in which,

Figure 1 is a vertical section of an apparatus embodying the invention taken on the line 1—1 of Fig. 2; Fig. 2 is a horizontal section on the line 2—2 of Fig. 1; and Fig. 3 is a section similar to Fig. 2 illustrating a modified form of the apparatus.

Referring to Figs. 1 and 2 of the drawing, 1 indicates a cylindrical vessel for containing disinfecting fluid and 2 a vertically arranged tube within the vessel, the lower end of the tube being sealed and connected with the bottom of the vessel by solder or other suitable means. An outlet is provided from the bottom of the central tube 2 to permit the fluid to drip from it. As shown, a small tube 3 is used for this purpose. In the annular space between the side wall of the vessel 1 and the tube 2 is arranged an annular float 4 which is free to rise and fall with the surface of the disinfecting fluid 5. The annular float 4 sustains a wick frame 6 which, as shown, comprises two upright portions connected to the float and a depending loop 7 extending down into the tube 2 the whole being formed of a continuous strip of metal. Connected to the wick frame is a continuous wick 8. The ends of the wick adjacent to the float are slightly higher than the loop 7 so that a siphonic action is created which gradually carries the disinfecting fluid

into the tube 2 from which it is discharged by the smaller tube 3. The apparatus so far described is an improvement upon Patent No. 641,548 issued to me January 16, 1900. By using the double wick the action of the apparatus is rendered more reliable and the float is more perfectly balanced and hence more certain in its action.

In disinfecting apparatus of the class above described the receptacle can be filled only to the top of the tube 2 and a considerable space must be allowed above the tube for the wick frame and wick. I utilize the annular space about the upper portion of the apparatus for a deodorizing apparatus which is preferably constructed as follows: 9 indicates a lid for the receptacle 1, which lid is provided centrally with a filling opening 10, closed by a spring stopper 11. Through this opening the disinfecting fluid is introduced into the vessel 1. Connected with the cover 9 is a depending tube 12, the lower end of which is carried outwardly at 13 to form an annular support for an annular wick 14. Extending up from the bottom 13 is an annular flange 15 which forms an annular receptacle at the bottom of the wick to hold deodorizing fluid. Above the wick are one or more filling openings 16 in the cover and the surrounding wall of the receptacle 1 is provided with perforations 17. The disinfecting fluid is poured in through the opening 16 until the wick or fibrous mass 14 is saturated, and, preferably, until there is a surplus of the fluid in the annular receptacle in which the wick 14 rests. The deodorizing fluid is volatile and the vapor and odor of it escape through the openings 17 into the atmosphere. The apparatus is connected to a wall or other suitable support by any suitable means, such as the ears 18, Fig. 2. In Fig. 3 I have shown my invention applied to a U-shaped receptacle having a flat back 19, which form is sometimes preferred.

According to my invention the deodorizing apparatus is connected to the detachable cover of the vessel containing the disinfecting apparatus. The casing of the disinfecting apparatus is usually attached to a wall or other fixed support and I am enabled to remove the deodorizing apparatus without disarranging it and without disturbing the disinfecting apparatus by re-

son of the construction described in which the deodorizing apparatus is permanently connected to the removable cover or cap of the casing. By making the deodorizing apparatus thus removable, I am also enabled to have access at any time to the interior of the disinfecting apparatus.

Having described my invention what I claim as new and desire to secure by Letters 10 Patent is,

1. In a combined disinfecting and deodorizing apparatus, the combination with a vertical casing provided in its lower part with a receptacle for disinfecting fluid, and 15 means for gradually discharging said fluid, of a detachable cover for said casing provided with a depending portion having a receptacle for deodorizing fluid, and a wick arranged to absorb the fluid from said re-

ceptacle and exposed to the atmosphere to 20 permit said fluid to evaporate, substantially as described.

2. In an apparatus of the class described, the combination with a casing 1 and a disinfecting apparatus therein, of a detachable 25 cover 9 having a depending tube, an annular portion 13 and a flange 15 connected to said tube and forming an annular receptacle for deodorizing fluid, and an annular wick resting in said receptacle and extending above 30 the flange 15, for the purpose set forth.

In testimony whereof I have signed my name to this specification in the presence of two subscribing witnesses.

WILLIAM H. ROSE.
